FISHING LURE

William J. Mincer, 11924 Pebblebrook Lane, Carmel,
Ind. 46032, and William L. Burtt, 11510 Trail's End,
Noblesville, Ind. 46060

Filed July 28, 1975, Ser. No. 600,358

Term of patent 14 years

Int. Cl. D22—05

U.S. Cl. D22—27

Fig. 1

Fig. 2

Fig. 3

Fig. 4

Fig. 5

FIG. 1 is a side elevational view of a fishing lure embodying our new design, the opposite side being identical thereto;

FIG. 2 is a rear elevational view;

FIG. 3 is a top view thereof;

FIG. 4 is a front elevational view thereof; and

FIG. 5 is a bottom plan view thereof.

We claim:

The ornamental design for a fishing lure, as shown and described.
